UNITED STATES PATENT OFFICE.

LOUIS DUQUESNOY, OF HIAWATHA, UTAH.

VALVE-GRINDING MECHANISM.

1,212,030.

Specification of Letters Patent.

Patented Jan. 9, 1917.

Application filed April 17, 1916. Serial No. 91,688.

To all whom it may concern:

Be it known that I, LOUIS DUQUESNOY, a citizen of the United States, residing at Hiawatha, in the county of Carbon and State of Utah, have invented new and useful Improvements in Valve-Grinding Mechanisms, of which the following is a specification.

This invention relates to valve grinding mechanism and more particularly to the hand operated type and it has for its primary object to so associate the elements of the mechanism that the valves will be accurately ground.

15 An object of the invention is to provide a valve grinding mechanism the parts of which are so associated that during the grinding operation the valve heads will be properly associated with their seats irrespective of the manner in which power is applied to the mechanism.

Another object of the invention is the novel manner of supporting the movable elements so that the same can be swung to a 25 position to allow access to the valve heads so as to readily determine whether the valves have been ground the proper amount.

Besides the above my machine is distinguished in the manner of associating the 30 driving mechanism with the valve heads so that different size valve heads can be accommodated and a tight fit had between the walls of the openings, the valve heads and the driving mechanism.

35 The invention will be better understood from the following detailed description taken in connection with the accompanying drawings wherein a preferred embodiment is illustrated and the features of novelty including all of the above mentioned and various others will be hereinafter pointed out in the appended claims.

In the drawings I have illustrated the apparatus as applied to a Ford engine but I 45 wish it to be understood that the same can be readily designed to accommodate any known type of engine.

Figure 1 is a top plan view of an engine showing the apparatus applied thereto. 50 Fig. 2 is a side elevation. Fig. 3 is an end elevation. Figs. 4 and 5 are cross sectional views on lines 4-4 and 5-5 of Fig. 1. Fig. 6 is a longitudinal view on line 6-6 of Fig. 1. Fig. 7 is an enlarged sectional view 55 of the valve head engaging device. Fig. 8

is a detail sectional view on line 8-8 of Fig. 7.

Referring to the drawings the numeral 1 designates a base provided with extensions so arranged as to engage the available space 6 between the engine cylinders. The base is effectively held against movement by means of machine screws 2 that pass through the base into the body of the engine. The base is further provided with a plurality of 65 standards 3 formed with alining openings 4 in which is rigidly mounted a cylindrical rod 5. At this point I wish to call attention to the fact that the base is so designed as to be secured to the engine in such a 70 manner as to expose the valve heads at all times.

Swingingly supported upon the rod 5 is a frame 6 composed of a lower plate 7 extending the length of the engine and auxiliary 75 upper plates 8 clamped to the lower plate by means of the machine screws 9. Thus it will be seen that the frame as a whole is free to move vertically in an arc of a circle so as to either take up a position directly 80 over the valve heads or a position to allow ready access to the valve heads. Passing through the rod 5 on opposite sides of one of the auxiliary plates 8 are pins 10, the purpose of which being to prevent longitudinal 85 movement of the frame upon the rod 5 so that the frame will be properly associated with the valve heads at all times.

Rotatably mounted in the frame between the plates 7 and 8 is a drive shaft 11 having 90 mounted thereon in this particular instance four duplex gears 12, one to each pair of valves. Meshing with each duplex gear 12 is a pair of gears 13 and 14 the shafts 15 of which being rotatably mounted in the plate 95 7 in alinement with the centers of two of the valve heads.

Those gears which are rotatably located in the plate 7 in alinement with the center of the valve heads support upon their shafts 100 a socket 16 the purpose of which is to receive the valve head engaging device now to be described. The valve head engaging device comprises a pair of members 17 and 18 jointed together at an intermediate point 105 by means of the pin 19. The members are so constructed that parallel end portions 20 are provided for engaging the usual poles 21 in the valve head and to have its remaining end portions 21' extending substantially 110

parallel to each other and adapted to be inserted in the socket 16. For increasing the frictional engagement between the extremities 20 and the openings 21 I mount in the 5 socket 16 a pointed screw 22 adapted when tightened to force in between the extremities 21 so as to vary the distance between the extremities 20 that engage the openings 21.

In the drawings I have shown means for 10 manually driving the shaft 11 but I wish it to be understood that the shaft 11 may be automatically driven from the engine. For this purpose I mount upon the shaft 11 a beveled gear 23 in mesh with another 15 beveled gear 24 upon a stub shaft 25 that has a squared extremity 26 adapted to be engaged by the crank handle 27.

To complete the invention I mount upon one of the standards 3 a spring 27 having a hook shaped extremity 28 adapted to engage a recess 29 in the plate 8, the purpose of this spring being to prevent vibratory movement 20 of the frame during the grinding operation.

It is to be understood that while all of the 25 several features of my improved machine have special coöperation with one another and together constitute a particularly effective mechanism for the purpose in view, certain of these features may be applied in 30 other relation such as having a direct connection between those gears carried by the frame and the valve heads thus dispensing with the members 17 and 18, and I therefore desire to cover the combination present in 35 the several parts of my improved machine whether employed in the general organization shown or elsewhere.

What I claim is:—

1. An engine valve grinder comprising a 40 base secured to the engine, a frame having a swinging connection with said base, a

shaft rotatably mounted in said frame, a set of gears mounted on said shaft, a second set of gears engaging said first gears and rotatably mounted in said frame, and means supported by said second set of gears for engaging the valve head. 45

2. An engine valve grinder comprising a base secured to the engine, a frame having a swinging connection with said base, a shaft 50 rotatably mounted in said frame, a set of gears mounted on said shaft, a second set of gears engaging said first gears and rotatably mounted in said frame, and means detachably supported by said second set of gears 55 for engaging the valve head.

3. An engine valve grinder comprising a base secured to the engine, a frame having a swinging connection with said base, a shaft 60 rotatably mounted in said frame, a set of gears mounted on said shaft, a second set of gears engaging the said first gears and rotatably mounted in said frame, and means having an adjustable detachable connection with said second set of gears and 65 arranged to engage the valve head.

4. An engine valve grinder comprising a base, a frame having a swinging connection with said base, a shaft mounted for rotation in said frame, a gear on said shaft, a second 70 gear rotatably mounted in said frame and having engagement with said first gear, pivoted valve engaging members carried by said second gear and a single element working between the members for giving adjustment thereto. 75

In testimony whereof I affix my signature in presence of two witnesses.

LOUIS DUQUESNOY.
